OVEN GAS COCK

John H. Grayson and Wayne E. Jenkins, Lynwood, Calif., assignors to Grayson Appliance Co. Ltd., Lynwood, Calif., a corporation of California

Application November 20, 1933, Serial No. 698,855

31 Claims. (Cl. 236—15)

This invention relates to a gas cock or valve specially designed and adapted for use in connection with an oven heat regulator and oven burner controlled thereby on a gas range.

5 The gas cock of our invention is one which operates a rod and tube type oven thermostat or regulator by means of a universal or flexible connecting rod, permitting a single dial control, that is to say, one operation accomplishes the 10 double function of opening the gas cock and setting the oven regulator. In the past, there have been unitary structures devised combining the gas cock and oven regulator directly, but such structures have invariably been too complicated and, furthermore, were impractical from the standpoint that the parts requiring cleaning, inspection, or repair, were not readily accessible, and we, therefore, prefer to have the 15 gas cock of our invention separate from the oven regulator and merely interconnected for joint 20 regulator and merely interconnected for joint operation in the manner stated.

In such combination controls, it has been difficult to provide properly for regulation of the oven burner for broiling; when the dial was 25 turned simultaneously with the gas cock to 550° or 600° F. for broiling, the broiling flame could not be turned low manually, and to turn back the gas cock to a lower flame would naturally mean a corresponding low temperature 30 setting of the oven regulator with the result that the oven burner would be extinguished. It is, therefore, the principal object of our invention to provide a gas cock, more specifically a disc 35 type valve or cock so constructed and with its gas delivery channels so arranged that it may be turned clockwise from "off", from the lowest to the highest indicated temperature, which is the broiling point, and then turned clockwise still farther to manually shut down the burner 40 independently of thermostatic action if it is desired to finish broiling with a low flame.

Another object is to provide a gas cock, as just described, in which at the highest indicated temperature (600°) the gas delivery channels 45 are properly related and proportioned to allow enough gas to flow to maintain that high temperature.

Still another object is to provide a gas cock of the kind described in which the rotor is reasonably locked in off position and there is required an outward pull on the knob or dial to turn to a selected temperature, the cock including spring means normally holding the rotor under constant pressure onto an accurately finished flat face on the stator to prevent leakage,

and another spring means normally urging the stem in one direction toward locked position so that, when the off position is reached, the rotor is automatically locked by means of the stem, and so that a predetermined frictional drag is imposed upon the turning of the stem otherwise to prevent accidental turning of the stem from a selected temperature setting.

The invention is illustrated in the accompanying drawings, in which—

Figure 1 is a longitudinal section through a gas cock made in accordance with our invention;

Fig. 1a is a detail view showing the lock for the stem of the gas cock;

Figs. 2 and 3 are plan and rear views, respectively;

Fig. 4 is a view of the flat channeled face of the rotor;

Fig. 5 is a view of the cooperating flat channeled face of the stator;

Figs. 6 to 9 are views similar to Fig. 5 but showing, in dotted lines the relationship of the channels in the rotor to the channels and ports in the stator in different positions to which the rotor is moved;

Fig. 10 is a plan view of a gas range illustrating the cock interconnected with the oven thermostat for a combination oven control, and

Fig. 11 is a vertical section through the oven thermostat taken on the line 11—11 of Fig. 10.

The same reference numerals are applied to corresponding parts throughout the views.

Referring first to Figs. 1 to 3, 10 designates the gas supply manifold extending from front to rear of the cooking top burner compartment and connected at its front end through a union 11 with the gas cock or valve of our invention, indicated generally by the numeral 12. This cock is of the disc type, comprising a stationary body or stator 13 and a rotary disc or rotor 14,

the stator having a flat face 15 channeled, as we shall point out presently, and accurately finished preferably by grinding and lapping to provide a good seat for the flat face 16 of the rotor that is correspondingly accurately finished. The face 16 is also channeled, as we shall point out later, so as to provide communication for a main outlet port 17 and a secondary outlet port 18 with an inlet port 19 in the stator. The ports 17 and 18 have passages 17' and 18' communicating therewith to deliver gas through pipes 17a and 18a to an oven burner 47 and pilot burner 48, respectively. The passage 19' in the stator communicates with the inlet port 19 to

deliver gas to said port from the manifold 10. The pipe connection 17a to the oven burner from passage 17' includes an oven heat regulator or thermostat 49, as disclosed in the copending application of John H. Grayson Serial No. 700,513 filed December 1, 1933, whereby to regulate the delivery of gas to the burner thermostatically to maintain with a selected oven temperature. Oven temperatures are selected in the turning 10 of the rotor 14 by means of stem 20 and knob 21 through the proper angularity from the off position, selected oven temperatures being indicated on a dial 22 by a pointer 23 mounted on any convenient stationary support, as, for example, directly on the stator 13, as at 24. The oven heat regulator or oven thermostat 49, as we shall refer to it hereinafter, is set coincidentally with the turning of the rotor 14 through a connecting rod 25 detachably and flexibly 15 joined to the inner end of the stem 20, as at 26. The aforesaid Grayson application contains a full disclosure of the operating connection between the other end of the rod 25 and the oven thermostat. It is clear from this much description 20 that the gas cock of our invention is intended for use as part of a combination control in which the turning of a single knob 21 and/or dial 22 results both in the turning on of the gas to the oven burner and its pilot burner at the 25 cock 12 and the setting of the oven thermostat through rod 25 for a selected oven temperature.

Fig. 10 shows the oven thermostat 49 as having the pipe 17a extended thereto from the cock 12 for delivery of gas to the thermostat, and another pipe 50 is shown extending from the thermostat to the oven burner 47 for delivery of gas to the burner as regulated by the thermostat. The pipe connection 18a from the cock 12 to the pilot burner 48 also clearly appears in this view, and the same is true of the rod connection 25 between the cock 12 and the control cam 51 of the thermostat 49. Turning the cam 51 results in setting the thermostat 49 for different oven temperatures as described in the 40 Grayson application. The thermostat is shown in cross-section in Fig. 11. It comprises a cast body 52 onto which a cap 53 is fastened. The latter supports a thermostat 54 of the rod and tube type. A member 55 movable with the end 45 of the rod element of the thermostat has a pointed end bearing in a recess formed in the middle of the fulcrum lever 56 housed in the gas-tight chamber 57 in cap 53. One end of the lever engages the stem 58 of the valve 59 controlling communication between inlet and outlet chambers 60 and 61 provided in the body 52. The pipe 17a previously referred to communicates with inlet chamber 60 and the pipe 50 with chamber 61. Consequently, as the valve 55 gradually opens or closes with cooling or heating 55 up of the oven, the oven burner flame gets larger or smaller. The oven temperature maintained depends upon the position of fulcrum 62 for the other end of the lever 56. The fulcrum is adjusted by the turning of the cam 51, the cam having a push rod 63 working in suitable guides for communicating movement from the cam to the plunger providing the fulcrum 62. A spring 64 normally urges the fulcrum plunger 62 and 60 push rod 63 in one direction toward the cam so that the position of the fulcrum changes as the cam is turned, in accordance with the contour of the cam, and, of course, it is understood that the cam is plotted in proper relation to the temperature scale on the dial 22 previously men-

tioned, so that different oven temperatures can be selected by merely turning the dial 22 and the cam 59 with it to different positions with respect to the pointer 23.

The cock 12, as clearly appears in Figure 1, has the rotor 14 centered with respect to the stator 13 on a sleeve 27 suitably secured in the center of the stator as with a press fit, and projecting forwardly therefrom, as shown. The rotor is centrally counterbored, as at 28, to accommodate a coiled compression spring 29 held under compression by a nut 30 threaded on the front end of the sleeve 27 and serving to hold the rotor 14 with its flat face 16 pressed against the flat face 15 of the stator 13 under sufficient pressure to keep the cock gas tight. The sleeve 27 also provides an external bearing on which the rotor turns, and an internal bearing for the stem 20, and not only keeps the rotor 14 centered with respect to the stator 13 but prevents 80 parting or separation on the faces 15 and 16 if pressure is exerted on the stem 20 downwardly, upwardly or sideways, through the instrumentality of the knob 21. It will also presently appear 85 how we have utilized the sleeve 27 as part of a locking means for holding the rotor 14 against turning. The latter stem 20 extends through the sleeve and projects from the back of the stator sufficiently to provide connection with the rod 25, and, where it projects, a coiled compression spring 31 is provided acting between the sleeve 27 and the sleeve part of the flexible connection 26 to urge the stem rearwardly. However, a pin 32 has its one end projecting 90 radially from the stem adjacent the front end 110 of the sleeve 27, and the projecting end enters a notch 33 formed in the end of the sleeve, as disclosed in Fig. 1a, whereby to prevent rearward movement of the stem and also hold the stem against turning until and unless the stem 115 is moved outwardly by means of knob 21 and/or dial 22 to disengage the end of the pin 32 from the notch 33, when, of course, the stem can be turned. The turning of the stem is limited to nearly 360° by a stop projection 34 formed on 120 the end of the sleeve 27 (Fig. 1a). In other words, after the stem is pulled out, it can be turned clockwise through almost a complete revolution until the end of the pin 32 strikes the 125 stop 34. We shall point out presently how the stem when pulled out and turned clockwise from off position brings the dial to its highest indicated temperature (600°) with respect to pointer 23 in about three-fourths, or 270°, of a complete turn, this being the broiling point, and 130 that the stem can then be turned clockwise still farther to regulate the flame of the oven burner independently of thermostatic action so as to shut it down if it is desired to finish broiling with a low flame. The dial 22 may, for that 135 reason, carry additional markings clockwise beyond the 600° mark with reference to size of broiling flame, as "high", "medium", and "low." The word "broil" may appear alone, or the word "toast", and at the limit of movement the word 140 "low" may be used in combination with either of these other words to indicate how the size of the flame is varied by turning the dial clockwise toward a limit position. The spring 31 causes the pin 32 to press against the front end of the 145 sleeve 27 sufficiently to exert the desired amount of frictional drag upon the turning of the stem, and this is considered desirable because the stem cannot be "spun", but will always turn smoothly, and will, furthermore, be less apt to be turned 150

accidentally from a set position. The stem 20, in order to permit of its being pulled out in the manner and for the purpose stated, must have a sliding driving connection with the rotor 14, 5 and that is provided through a jaw clutch consisting of a collar 35 suitably fixed on the stem 20 behind the dial 22, and having jaws 36 projecting rearwardly therefrom and slidably received in notches 37 provided in the front end 10 of the rotor 14. The collar 35 forms a support for the dial 22, as shown.

Referring now to Figs. 4 to 9, and to begin with more particularly, Figs. 4 and 5, it will be seen that the inlet port 19 is diametrically opposite the outlet port 17 and on the same radius, and that the secondary or pilot outlet 18 is midway between ports 17 and 19 and on the same radius. The stator face 15 has an arcuate channel *a* formed therein on the same radius 15 with the three ports 17—19, and as wide as ports 17 and 19, and reaching both clockwise and counterclockwise from port 17, the channel including approximately 180°. The port 18 has a much shorter arcuate channel *b* extending therefrom in a clockwise direction, approximately 30°, and of the same width as the port. Another channel *c* communicates with port 19 and extends in an arc a short distance, approximately 30°, in a counterclockwise direction from said port. The depths of channels *a* and *c* are shown 20 in Figure 1, channel *b* being the same depth as channel *c*, namely, about half the depth of channel *a* and less than half the width. Rotor 14 has two arcuate channels *d* and *e* formed in its face 16 on the same radius with ports *a*, *b*, and *c* of stator 13. Channel *d* is of the same width as channel *a* and extends for approximately 225°. Channel *e* is of the same width as channels *b* and *c* and extends for approximately 90°, being 25 midway between the ends of channel *d*, as clearly appears in Fig. 4.

Referring now to Fig. 6, channels *d* and *e* of rotor 14 are indicated in dotted lines in the relationship they assume to channels *a*, *b*, and *c* of stator 13 when the rotor is in the off position. It is clear from this figure that the inlet port 19 is completely cut off from any communication with ports 17 and 18, although channel *d* is superimposed on channels *a* and *b*, and 30 channel *e* is superimposed on channel *c*. Fig. 7 shows what results from a slight turn of the rotor in a clockwise direction; the port 19 is thrown into communication simultaneously with ports 17 and 18 by reason of the fact that the adjacent ends of channels *d* and *e* come into 35 communication with port 19, the channel *e* delivering gas to one end of channel *a* so that gas flows in small amount to the oven burner through port 17 and also to the pilot burner through port 18, additional gas being delivered 40 through channel *c* to channel *d* and thence to ports 17 and 18. The oven burner and pilot burner are, therefore, supplied with gas and may be ignited either by an automatic oven lighter or in the old way. Now, if the rotor 14 is turned farther in a clockwise direction, it is 45 apparent that channel *d* comes into greater and greater communication with port 19 and finally full communication, and the continued turning, of course, adjusts the oven thermostat for higher and higher temperatures until the highest indicated temperature of 600° is reached, which is 50 the broiling point. Fig. 8 shows the rotor advanced approximately 180°, that is a half turn 55 from off position with a full delivery of gas

indicated via channels *d* and *a* to the oven burner, and it is apparent that one may continue turning in a clockwise direction for another 90° and still maintain full communication between channels *d* and *a*. At the end of such movement, the dial indication will be 600°, that is the broiling point, and, with this full communication, there is nevertheless sufficient surface contact at 15—16 for an adequate gas seal. Furthermore, there is sufficient communication between ports 17 and 19 at these high temperatures for enough gas to flow to maintain such temperatures, which is not true of some other gas cocks that have come to our attention. In the turning of the rotor still farther in a clockwise direction, it is apparent that the end of the channel *d* has less and less communication with port 19, and, consequently, the operator is enabled thereby to shut down the oven burner independently of thermostatic action if he desires to finish broiling with a low flame. Fig. 9 shows the relationship of the channels at the limit point when pin 32 strikes the stop 34 at the broiling end of the rotation of the dial, and it will be seen that the pilot 100 burner is still supplied with gas by reason of channel *e* establishing communication between channels *b* and *c*, although the main burner has been extinguished. It is apparent, therefore, that manually controlled broiling can be 105 done with the burner shut down to the lowest possible flame, and we avoid the objectionable condition met with in other combination controls where no provision was made for manually controlled broiling, and turning back the gas 110 cock to a lower flame for such purposes resulted in the burner being extinguished. In other words, we secure with this invention the equivalent of what was obtained with the old arrangement where the oven thermostat was separately 115 operated independently of the oven cock, and the operator, in controlling the broiling flame, would set the oven thermostat for the highest temperature and then manipulate the oven cock to regulate the oven burner flame as desired. 120 The improvement of a combination control, making manually controlled broiling possible by manipulation of the same knob after turning the dial up to and past the highest indicated oven temperature, is manifestly of great advantage and eliminates all danger of confusion on the part of the housewife.

It is believed the foregoing description conveys a good understanding of the objects and advantages of our invention. The appended 125 claims have been drawn with a view to covering all legitimate modifications and adaptations.

We claim:

1. In a device of the character described, comprising an oven and a main burner therefor 130 having a standby pilot burner, a thermostatically controlled valve for said main burner having a manual setting means for selection of oven temperatures, a manually controlled valve for controlling flow of fuel from a supply source 140 to said thermostatic valve and to said pilot burner, and a single manually operable control for simultaneously opening the second valve and adjusting the temperature setting means of the first valve for a selected oven temperature, the second valve being so constructed in relation to the first valve and the temperature setting means of the first valve, whereby 145 the second valve is arranged to be gradually closed to the oven burner in turning the control 150

- beyond the highest oven temperature, but remains open to the pilot burner.
2. A structure as set forth in claim 1 including a single temperature dial with relation to which the single manually operable control is operated for setting the thermostatic valve to higher and higher oven temperatures in movement of the control from a starting position, the dial including broiling indications beyond the range of readings of oven temperatures.
3. In a device of the character described, comprising an oven and a main burner therefor having a standby pilot burner, a thermostatically controlled valve for said main burner having a manually rotatable setting means for selection of oven temperatures, a manually controlled valve for controlling flow of fuel from a supply source to said pilot burner and to said oven burner through said thermostatic valve, said valve being rotatable from one closed position in which it is closed to the pilot burner and oven burner, through a range of open positions to another closed position in which it is closed to the oven burner but remains open to the pilot burner, means for limiting the turning of the valve to approximately one complete turn, and a single manually rotatable member for turning said valve and simultaneously turning the oven temperature setting means, said second valve being so constructed relative to the first valve and its setting means whereby the ultimate closing of said second valve occurs in turning a certain distance beyond the normal range of oven temperatures in which the gas flow to the oven burner is gradually diminished to zero but is continued to the pilot burner, whereby to permit manually controlled broiling independent of thermostatic action.
4. A structure as set forth in claim 3 including an oven temperature dial member and a cooperating pointer member, the one member being mounted to turn with the single manually rotatable member to indicate directly selected oven temperatures, said dial including a range of oven temperatures and, beyond the highest normal oven temperature, a range of broiling indications.
5. In a combination oven control, a single manually rotatable stem, a disc type gas cock comprising a stator, and a rotor turning with said stem, the stator and rotor having gas conducting channels provided therein for controlling flow of gas from an inlet port to a main and a secondary outlet port provided in the stator, the inlet port having communication with a gas supply and the main outlet with an oven burner and the secondary outlet with a pilot burner for the oven burner, and a thermostatic oven valve having a rotatable control member turned by connection with said stem, said cock having its stator and rotor channels so constructed and arranged relative to the control member, whereby to permit turning the rotor to shut down the gas to the oven burner while the thermostatic valve is kept set for a high oven temperature.
6. A structure as set forth in claim 5 including a dial bearing oven temperature graduations and mounted to turn with said stem relative to a stationary pointer, the dial having broiler indications beyond the highest oven temperature with successively smaller broiler flame values farther and farther from the highest of the oven temperature graduations.
7. A structure as set forth in claim 5 including spring means normally urging the stem endwise relative to the cock in one direction, a stationary sleeve relative to which said stem is rotatable and movable endwise, a detent projection on said stem received in a recess in the end of said sleeve to lock the stem releasably in an "off" position, and means providing a sliding driving connection between the stem and the rotor of the cock.
8. A structure as set forth in claim 5 including spring means normally urging the stem endwise relative to the cock in one direction, a stationary sleeve relative to which said stem is rotatable and movable endwise, a detent projection on said stem received in a recess in the end of said sleeve to lock the stem releasably in an "off" position, and means providing a sliding driving connection between the stem and the rotor of the cock, said sleeve passing through said rotor as a guide therefor, and said rotor having spring means acting between the sleeve and rotor to press the rotor into gas tight sealing engagement with the stator.
9. In an oven burner control of the type 100 wherein a gas cock and a thermostatic oven heat regulator are interconnected for operation by one control for simultaneously opening the cock and setting the regulator for a desired oven temperature, a gas cock constructed so as to 105 throttle down the flow of gas to the oven burner independently of thermostatic action when the control is moved beyond the normal oven temperature range.
10. In an oven burner control of the type 110 wherein a gas cock and a thermostatic oven heat regulator are jointly operated by a single control, a gas cock so constructed and so related to the control and regulator, whereby it is arranged to throttle the flow of gas to the burner for 115 broiling, independently of thermostatic action of the regulator.
11. A disk type gas cock comprising a rotor, and a stator having a gas inlet port and a gas outlet port provided therein in diametrically 120 opposed relation and a smaller secondary gas outlet port provided therein substantially midway between the other ports, all on approximately the same radius with respect to the axis of rotation of the rotor, the stator having a flat 125 seat and the rotor having a flat face to engage the seat, the rotor having two arcuate channels provided in its flat face on the same radius as said ports, the one extending throughout more than 180° and of the same width as 130 said main ports, and the other being narrower and of the same width and on the same radius as the secondary port and disposed substantially midway between the ends of the other channel.
12. A cock as set forth in claim 11, wherein the stator has an arcuate channel provided in its seat on the same radius as the main outlet port and of the same width, extending in both directions from the port through substantially a half circle.
13. A cock as set forth in claim 11, wherein the stator has arcuate channels provided in its seat of the same width as the secondary outlet port and on the same radius with said port, the one channel extending from the secondary outlet port toward the inlet port, and the other extending from the inlet port toward the secondary outlet port, the ends of said channels being spaced a predetermined distance.

14. A cock as set forth in claim 11, wherein the stator has arcuate channels provided in its seat of the same width as the secondary outlet port and on the same radius with said port, the one channel extending from the secondary outlet port toward the inlet port, and the other extending from the inlet port toward the secondary outlet port, the ends of said channels being spaced a predetermined distance, and wherein 10 said stator has another channel provided in its seat on the same radius as the main outlet port and of the same width, extending in both directions from the port through substantially a half circle. 15 140
15. A cock as set forth in claim 11, wherein the stator has arcuate channels provided in its seat of the same width as the secondary outlet port and on the same radius with said port, the one channel extending from the secondary outlet port toward the inlet port, and the other extending from the inlet port toward the secondary outlet port, the ends of said channels being spaced a predetermined distance, so that they may be interconnected by the narrower channel 20 of the rotor, when the same is disposed in register with said stator channels. 25 145
16. A disk type gas cock comprising a rotor, and a stator having a gas inlet port and a gas outlet port provided therein in diametrically opposed relation and a smaller secondary gas outlet port provided therein substantially midway between the other ports, all on approximately the same radius with respect to the axis of rotation of the rotor, the stator having a flat seat 30 and the rotor having a flat face to engage the seat, the rotor having two arcuate channels provided in its flat face on the same radius as said ports, the one extending throughout approximately 225° and of the same width as the main 35 ports, and the other being narrower and of the same width and on the same radius as the secondary port and disposed midway between the ends of the other channel, extending approximately 90°. 40 150
45. 17. In a combination oven control, the combination with a source of gas supply, an oven thermostat supplied with gas from said source, an oven burner to which gas is delivered in regulated amounts from the thermostat, and a pilot burner therefor, of a rotary gas cock interposed between the source and the oven thermostat and pilot burner, means interconnecting the rotary part of the gas cock with the thermostat whereby turning of the gas cock results in simultaneous setting of the thermostat, the gas cock having gas passages so constructed and arranged whereby in a single turn of its rotary part from one limit position to another limit position to first supply gas to the pilot burner and oven burner while setting the thermostat for a selected oven temperature, subsequently cut down gas to the oven burner while leaving the oven thermostat at a high temperature setting, and finally supply gas only to the pilot burner at the limit position of the rotary part, and means for turning the rotary part of said cock. 50 155
18. A disk type cock comprising a stator having a flat seat, a rotor having a flat face to engage the seat, the stator and rotor having passages provided therein arranged to have different communication in different positions of the rotor relative to the stator, a sleeve fixed in a central opening provided in the stator and projecting therefrom, normal to the plane of the flat seat, 70 through a registering central hole provided in 75 160
- the rotor whereby to locate the rotor in centered relation to the stator and serve as a bearing for the rotor in the turning thereof relative to the stator, with the flat face of the rotor always fully engaged with the flat seat on the stator, an operating stem rotatably mounted in the sleeve as a bearing and loosely connected with the rotor to turn the latter, the sleeve supporting the stem independently of the rotor, and spring means normally urging the rotor toward the stator. 80 165
19. In a combination oven control for an oven burner and pilot burner, a thermostatic valve having gas passages for delivery of gas to the oven burner in regulated amount and having a rotary temperature adjustment, a rotary gas cock having gas passages communicating with the open burner through the thermostatic valve and also having communication with the pilot burner, and a single manually rotatable control operatively connected with said cock and temperature adjustment to permit simultaneously opening the cock to the burners and setting the thermostatic valve for a selected oven temperature, said cock having its passages so constructed and arranged whereby, after such opening, the cock may be turned further toward a broil position to shut down on the oven burner but not on the pilot burner. 90 170
20. In a combination oven control for an oven burner and pilot burner, a thermostatic valve having gas passages for delivery of gas to the oven burner in regulated amount and having a rotary temperature adjustment, a rotary gas cock having gas passages communicating with the open burner through the thermostatic valve and also having communication with the pilot burner, and a single manually rotatable control operatively connected with said cock and temperature adjustment to permit simultaneously opening the cock to the burners and setting the thermostatic valve for a selected oven temperature, said cock having its passages so constructed and arranged relative to the control and temperature adjustment, whereby, after such opening of the cock, and beyond the highest temperature setting of the temperature adjustment, the cock may be turned further to throttle the oven burner independently of thermostatic regulation, said cock continuing to supply gas in undiminished amount to the pilot burner. 105 175
21. In an oven burner control, the combination with an oven burner and a pilot burner, of a rotary gas cock having gas passages for delivering gas to the oven burner and pilot burner, said passages being so constructed and arranged whereby in turning the cock from one limit position to another to first supply gas to the pilot burner at a certain rate and to the oven burner at a certain rate and thereafter in the further turning of the cock approaching the other limit position, to gradually diminish and finally shut off the gas flow to the oven burner but continue the gas flow to the pilot burner. 110 180
22. In an oven burner control, the combination with an oven burner and a pilot burner, of a rotary gas cock having gas passages for delivering gas to the oven burner and pilot burner, said passages being so constructed and arranged whereby in a cycle of turning movement of the cock from one limit position to another to first open the cock to the two burners, and thereafter, starting with a certain flow to the oven burner, gradually increasing to a peak flow and 135 190

- then gradually decreasing to zero flow, and, starting with a certain flow to the pilot burner, continuing with substantially the same flow all the way to the other limit position of the cock. 80
- 5 23. In a gas range, a manifold for supplying gas, a thermostatic device for regulating gas flow to an oven burner, and a single gas valve interconnected with the thermostatic device for simultaneously setting the device for different 85 temperatures in the operation of the valve, said valve being so constructed whereby in one range of operation to supply gas to an oven burner and its pilot burner so that the oven burner alone is under thermostatic control of the thermostatic device, and in another range of operation to supply gas to an oven burner and its pilot burner so that the oven burner alone is under throttling control of the valve, independently of the thermostatic device. 90
- 10 24. A disk type cock comprising a stator element having a flat seat, a rotor element having a flat face to engage the seat, the stator and rotor elements having passages provided therein arranged to have different communication 95 in different positions of the rotor element relative to the stator element, a sleeve fixed in a central opening provided in the one element and projecting therefrom, normal to the plane of the flat seat and face, through a registering central hole provided in the other element whereby to locate the elements in centered relation to one another and serve as a bearing for the one element on the other, an operating stem extending through the sleeve and 100 loosely connected with the rotor to turn the latter, and spring means normally urging the rotor toward the stator. 105
- 15 25. A disk type cock comprising a stator having a flat seat, a rotor having a flat face to engage the seat, the stator and rotor having passages provided therein arranged to have different communication in different positions of the rotor relative to the stator, a sleeve fixed in a central opening provided in the stator and projecting therefrom, normal to the plane of the flat seat, through a registering central hole provided in the rotor whereby to locate the rotor in centered relation to the stator and serve as a bearing for the rotor in the turning thereof relative to the stator, with the flat face of the rotor always fully engaged with the flat seat on the stator, an operating stem rotatably mounted in the sleeve as a bearing and loosely connected with the rotor to turn the latter, the sleeve supporting the stem independently of the rotor, an interfitting projection and recess on the stem and sleeve for detachably locking the stem and rotor against turning, said stem being movable endwise in one direction with respect to the sleeve to disengage the projection and recess to permit turning of the stem and rotor, and spring means normally tending to move the stem in the opposite direction. 110
- 20 26. A disk type cock comprising a stator having a flat seat, a rotor having a flat face to engage the seat, the stator and rotor having passages provided therein arranged to have different communication in different positions of the rotor relative to the stator, a sleeve fixed in a central opening provided in the stator and projecting therefrom, normal to the plane of the flat seat, through a registering central hole provided in the rotor whereby to locate the rotor in centered relation to the stator and serve as a bearing for the rotor in the turning thereof relative to the stator, with the flat face of the rotor always fully engaged with the flat seat on the stator, an operating stem rotatably mounted in the sleeve as a bearing and loosely connected with the rotor to turn the latter, the sleeve supporting the stem independently of the rotor, an interfitting projection and recess on the stem and sleeve for detachably locking the stem and rotor against turning, said stem being movable endwise in one direction with respect to the sleeve to disengage the projection and recess to permit turning of the stem and rotor, and spring means normally tending to move the stem in the opposite direction. 115
- 25 27. A disk type cock comprising a stator having a flat seat, a rotor having a flat face to engage the seat, the stator and rotor having passages provided therein arranged to have different communication in different positions of the rotor relative to the stator, a sleeve fixed in a central opening provided in the stator and projecting therefrom, normal to the plane of the flat seat, through a registering central hole provided in the rotor whereby to locate the rotor in centered relation to the stator and serve as a bearing for the rotor in the turning thereof relative to the stator, with the flat face of the rotor always fully engaged with the flat seat on the stator, spring means surrounding the sleeve and urging the rotor toward the stator, an operating stem rotatably mounted in the sleeve, a handle on the stem slidably connected with the rotor to turn the same, a projection turning with the handle and detachably engaging in a recess provided in the end of the sleeve to lock the rotor against turning, the projection being disengageable from the recess by endwise movement of the handle in one direction relative to the rotor, and spring means normally tending to move the handle endwise in the opposite direction. 120
- 30 28. A disk type cock comprising a stator having a flat seat, a rotor having a flat face to engage the seat, the stator and rotor having passages provided therein arranged to have different communication in different positions of the rotor relative to the stator, a sleeve fixed in a central opening provided in the stator and projecting therefrom, normal to the plane of the flat seat through a registering central hole provided in the rotor whereby to locate the rotor in centered relation to the stator and serve as a bearing for the rotor in the turning thereof relative to the stator, with the flat face of the rotor always fully engaged with the flat seat on the stator, spring means surrounding the sleeve in front of the rotor and urging the rotor toward the stator, an operating stem rotatably and slidably mounted in the sleeve and extending therethrough, the front end of said stem being connected with the rotor to turn the same, a projection on the stem engageable in a recess provided in the front end of the sleeve to lock the stem and rotor against turning, said projection being disengageable from the recess by forward movement of the stem relative to the sleeve, and spring means surrounding the projecting rear end of said stem normally tending to move the stem rearwardly, the projecting rear end of said stem being adapted for connection with another part to be rotated with the stem. 125
- 35 29. A disk type cock as set forth in claim 18 including means on the stem arranged to engage means on the sleeve to limit rotation of the stem with respect to the sleeve and thus con- 130

trol the turning of the rotor relative to the stator.

30. A disk type cock as set forth in claim 25 wherein the projection for engagement in the recess is provided on the stem, the cock including another projection on the end of the sleeve for engagement by the projection on the stem to limit turning of said stem, whereby to control the turning of the rotor relative to the stator.

31. A disk type cock as set forth in claim 27 including a projection on the sleeve arranged for engagement by the projection turning with the handle whereby to limit turning of said handle and thereby control turning of the rotor with respect to the stator.

JOHN H. GRAYSON.
WAYNE E. JENKINS.

CERTIFICATE OF CORRECTION.

Patent No. 1,977,552.

October 16, 1934.

JOHN H. GRAYSON, ET AL.

It is hereby certified that error appears in the printed specification of the above numbered patent requiring correction as follows: Page 5, line 93, claim 19, for the word "open" read oven; and that the said Letters Patent should be read with this correction therein that the same may conform to the record of the case in the Patent Office.

Signed and sealed this 8th day of January, A. D. 1935.

(Seal)

Leslie Frazer
Acting Commissioner of Patents.
